UNITED STATES PATENT OFFICE

HARRY E. BOYRIE, OF SAN FRANCISCO, CALIFORNIA, ASSIGNOR, BY MESNE ASSIGNMENTS, TO BLAW-KNOX COMPANY, OF BLAWNOK, PENNSYLVANIA, A CORPORATION OF NEW JERSEY

FLUID SEPARATOR

Application filed April 29, 1925. Serial No. 26,566.

This invention relates to fluid separators, and it has for its object an improvement on an ordinary type of fluid separator such as that illustrated and described in the Patent No. 5 1,336,870 issued to H. H. Tracy, April 13, 1920. My improvement consists partly in more suitably proportioning certain parts of a fluid separator of this general type.

Of the drawings, Fig. 1 is a cross sectional 10 view of a fluid separator or purifier which embodies the features of my invention; Fig. 2 is a central transverse section of the purifier; Fig. 3 is an elevation of a purifier mounted in a boiler for operation, the purifier consisting 15 of eight sections; and Fig. 4 is an enlarged central sectional view of a portion of the purifier similar to Fig. 3, but comprising three sections only.

The separator which I have illustrated is 20 ordinarily installed in the steam boiler 110 and the separator comprises a casing 111 which forms the exterior portion of the separator. To this casing are attached cartons 112 of 25 baffles 113 which dry and purify the steam or gas as it passes from the boiler through the baffles to the interior chambers. From the separator the steam passes out of the boiler through an outlet 114 which is connected to the steam supply main of the boiler. The 30 steam passes from the baffles 113 into the chamber 115, through the slot passageway 116, into the interior conduit or chamber 117, and thence into the separator outlet 108 and the boiler outlet 114.

The interior chamber 117 is enclosed by a 35 casing comprising walls 118 forming its sides and a bottom 119 and over the chamber is a plate 120 which is elevated above the side walls so as to form the slot 116 through which the steam enters the interior chamber. In 40 practice the separators are of considerable length and frequently comprise several sections, as indicated in Fig. 3 which has four sections on one side of the outlet and corresponding sections on the other side of the out-

let. The slots 116 extend substantially the full length of each section and form an inlet for the steam from the baffles. The baffles extend substantially from the steam outlet 108 to the remote end of the farthest section. 50 The steam, however, entering this slot inlet 116 must all pass through the passageway 117 to the outlet 108.

As a consequence of this arrangement, 55 there is a tendency for the steam to pass through the baffles more rapidly as the outlet is approached, because of the back pressure generated in the chamber 117 being less nearer the outlet. To offset this it has been found desirable to taper the slot inlet 116 by decreasing the width of the slot as the outlet is approached so as to restrict more and more the flow of the steam into the interior chamber. It is desirable to maintain at all times 60 substantially a uniform rate of flow of the steam through the baffles, and in order to accomplish this I find it desirable to not only provide a tapering slot for the steam inlet, by increasing the elevation of the plate 120 as 65 the outer end of the separator is approached, but also to increase this elevation at a rate greater than the rate of approach to the outer end.

In practice it is not convenient to change 70 the rate of increase in the elevation of any of the uppermost plates as the outer end is approached, and hence I have not so shown it in the drawings, but theoretically there should be a slightly greater elevation in proportion to the distance from the steam outlet 75 as the outer free end of the purifier is approached. In practice this can be approximated by increasing the inclination of each plate 120 from section to section, having the inclination of the plate of the second section more than that of the first section and of the third section more than that of the second, and so on. In Fig. 4 I have shown three sections with this varying inclination of the plate 120. It will be seen that the inclina- 80 85 90 95

tion of the plate of the outer section 125 is greater than the inclination of the plate of the section 126, and the inclination of the plate of section 126 is greater than the inclination of the plate of section 127. In this way the rate of flow through the baffles in the different sections is more nearly equalized. It is to be understood, however, that to substantially equalize the flow through the baffles 10 it would be necessary for slot 116 to continuously enlarge at a greater rate than the distance from the outlet.

It is desirable to very rapidly enlarge the inlet adjacent the outer end of the outer section so as to increase the steam flow at this end. In practice, therefore, it is desirable to have the sides 118 and 120 of the outer section terminate before reaching the outer end of the section, (Fig. 4), so as to leave 15 a very large passageway 129 for the steam at this point. Ordinarily I prefer to have these sides terminate about 6" from the end of the end section, and to have the width of the slot at this point about 1". It will be understood, 20 however, that these dimensions are merely for illustrating and approximate only what a good slot arrangement would be for the purifier of the other dimensions specified.

Although I have described with much particularity a fluid separator to be used for purifying steam, yet it is to be understood that separators having slots substantially as herein set forth for the passage of the fluid therethrough could be used for various other 25 purposes, such as eliminating impurities from various other gases, and separating fluids of different densities. Also other eliminating apparatus for the passage of fluids could be used with similarly proportioned slots, for 30 instance, apparatus for ventilating rooms by withdrawing the air uniformly into an elongated cooler, having an end outlet; or apparatus for injecting air into a room; or apparatus for the purpose of withdrawing a 35 mixture of liquids uniformly along its length, and various other apparatus. It is understood that the illustrations herein made are merely for the purpose of definitely describing my invention.

50 I claim:

1. A gas purifier comprising an elongated casing having a gas outlet adjacent one end and a gas inlet extending along one side of said casing, said inlet having purifying means mounted therein, and means for retarding the flow of gas mounted in said casing, said means comprising plates forming an inner chamber, said plates having an elongated slot therein, the end of said plates most 55 remote from said outlet being spaced a material distance away from the adjacent end of the casing.
2. A fluid separator comprising an elongated casing, a series of baffles mounted in one side of said casing, said casing having an out-

let adjacent one end thereof, and gas retarding means mounted between said baffles and said outlet, all of said retarding means being spaced a material distance from the end of said casing most remote from said outlet, 70 said retarding means comprising an inner conduit.

3. A fluid separator comprising an elongated casing, a series of baffles mounted in one side of said casing, said casing having an outlet adjacent one end thereof, and gas retarding means mounted between said baffles and said outlet, all of said retarding means being spaced a material distance from the end of said casing most remote from said outlet, 75 said retarding means comprising an inner conduit, 80 said conduit having an elongated slot running from one end to the other.

4. A fluid separator comprising an elongated casing, a series of baffles mounted in one side of said casing, said casing having an outlet adjacent one end thereof, and gas retarding means mounted between said baffles and said outlet, all of said retarding means being spaced a material distance from the end 85 of said casing most remote from said outlet, 90 said retarding means comprising an inner conduit, said conduit having an elongated slot running from one end to the other, said slot increasing in width as said outlet is re- 95 ceded from.

5. A fluid receiver comprising an elongated casing, said casing having an outlet, an interior conduit in said casing, said conduit having an elongated inlet extending substantially from one end to the other, the end of said conduit most remote from said outlet being open and being spaced a material distance from the adjacent end of said casing.

6. A fluid receiver comprising an elongated casing having a fluid outlet, and an elongated fluid inlet, the end of said inlet most remote from said outlet being enlarged relative to the remaining portions of said inlet and extending across the adjacent end of the 105 casing.

7. A fluid separator comprising an elongated casing, a series of baffles mounted in one side of said casing, said casing having a gas outlet positioned a long distance from 110 one end of the casing, an inner conduit extending longitudinally in said casing between said baffles and outlet, said conduit communicating with said outlet and extending therefrom towards a remote end of said casing but terminating a material distance before said end is reached, said conduit having a slot in its walls extending substantially from one end to the other.

8. A fluid separator comprising an elongated casing, a series of baffles mounted in one side of said casing, said casing having a gas outlet positioned a long distance from one end of the casing, an inner conduit extending longitudinally in said casing between said 125 130

baffles and outlet, said conduit communicating with said outlet and extending therefrom towards said end of said casing but terminating a material distance before said end is reached, said conduit having a slot in its walls extending substantially from one end to the other, and said slot increasing in width as said outlet is receded from.

5 In testimony whereof, I hereunto set my
10 hand.

HARRY E. BOYRIE.
